(57) **CLAIM**

The ornamental design for a steak cooker, as shown and described.

DESCRIPTION

FIG. 1 is a top perspective view of the steak cooker showing our new design.

FIG. 2 is a right-side view thereof.

FIG. 3 is a left side view thereof.

FIG. 4 is a top view thereof.

FIG. 5 is a bottom view thereof.

FIG. 6 is a rear view thereof.

FIG. 7 is a front view thereof; and,

FIG. 8 is a side view in a folded configuration.

Broken lines shown illustrate portions of the steak cooker that form no part of the claimed design.

1 Claim, 3 Drawing Sheets
